UNITED STATES PATENT OFFICE.

HOWARD D. HODGE, OF BRIDGEPORT, CONNECTICUT, ASSIGNOR TO NOBEL'S EXPLOSIVES COMPANY, LIMITED, OF GLASGOW, SCOTLAND.

CARTRIDGE-SHELL-FEEDING MACHINE.

971,999.

Specification of Letters Patent.

Patented Oct. 4, 1910.

Application filed August 6, 1907. Serial No. 387,327.

To all whom it may concern:

Be it known that I, HOWARD D. HODGE, a citizen of the United States, and a resident of Bridgeport, in the county of Fairfield 5 and State of Connecticut, have invented certain new and useful Improvements in Cartridge-Shell-Feeding Machines, of which the following is a specification.

My invention relates to improvements in 10 automatic cartridge shell feeding machines, and it consists in certain details of construction to be more fully set forth in the following specification and such features believed to be new and novel to be particularly pointed 15 ed out in the claims.

To enable others to understand my invention, reference is had to the accompanying drawings in which:

Figure 1—represents an upper plan view 20 of the machine. Fig. 2—a side elevation and broken sectional view of the floor. Fig. 3—is an enlarged central sectional view of the dial and its supporting base. Fig. 4—is an enlarged broken sectional view of the 25 shell feeding tube.

The machine is adapted for automatically taking shells from a hopper and feeding them to a loading machine situated on a lower plane. Machines of this character 30 are usually located in a room or story above the story where the loading machine is situated.

The object of the present improvement is to feed the shells to the loading machine 35 with the mouth of the shell always and invariably uppermost. To this end, the construction and operation of the machine are as follows:

1—is the hopper for holding the shells 40 in bulk.

2—is an endless carrier or band provided on its exterior with the buckets —2^a— between which the shells are located while being carried from the hopper to the machine. 45 3—is a horizontal shaft carrying the feed band pulley —5—, and —6—is an upper feed band pulley mounted on the short shaft —7— journaled in the bracket —8—, and —9—is an idler on the short shaft —10—, 50 which shaft is also journaled in said bracket.

11—is an open chute through which the feed band runs from the hopper, and —12—is an idler for said band journaled in the chute.

55 13—is the dial journaled on a projection

of the stationary support —14— and is held in a rotatable position thereon by the cap —15—. This dial is caused to rotate at a slow rate of speed through the medium of the following mechanism, viz: 16—is a vertical driving shaft journaled in the brackets —17— and —18— of the frame —19— and carries the grooved pulley —20— and belt —21—, which belt runs in the grooved edge of the dial. 22—is a bevel gear on this shaft 65 meshing with the bevel gear —22^a— mounted on one end of the short horizontal shaft —23— journaled in the bracket —18—. 24—is another bevel gear on the opposite end of this short shaft meshing with the bevel gear 70 —24^a— on the end of the long horizontal shaft —3—.

25—is an outer guard secured to the dial support —14— and it projects above the dial a distance greater than the diameter of 75 a shell.

26—is an inner guard secured to the outer guard by the bridges —27— so that, the space between these guards form a channel way for the shells for the purpose presently 80 to be more fully described. The outer edge of the dial —13— projects into this channel and is allowed to rotate under the inner guard —26—.

The upper surface of the dial is made 85 preferably crowning or slightly cone shaped so that the shells —a—, when they fall from the endless carrier upon the dial, will naturally roll toward the outer edge and against the inner guard —26—, in which position it 90 is easily maintained by the outer beveled edge —13^a— of the dial. The length of this beveled edge, from its commencement on the face of the dial to the inner face of the guard —26—, being less than the diameter of a 95 shell will prevent two shells riding abreast of one another on this beveled edge.

As before mentioned, the purpose of the two guards —25— and —26— is to form a channel way for the shells to enter and be 100 conveyed to a discharging point presently to be described. This channel way is of circular construction beginning at the point —b—, Fig. 1— and terminating at about the point —c—. Between these two points 105 the channel way will be designated as —d—, and from the point —c— this channel way continued straight with a downward pitch or inclination and is designated as —e—. While the sides or guards, of this channel 110

way —e— are but a continuation of the guards —25— and —26— they will, to avoid confusion, be designated as —25^a— and —26^a—.

5 As the shells are dropped upon the dial from the endless carrier, they gravitate, as before mentioned, against the inner guard —26— and, while some will lie on the incline —13^a— of the dial, others will lie 10 against the shells thus located in the true path of rotation so that, when the point —c—, Fig. 1— is passed, and there being no inner guard until the point —b— is reached, the full width of the outer incline —13^a— 15 of the dial is exposed so that two shells can ride abreast. To prevent two shells entering the channel way at the point —b—, the brushes —28— and —29— —see also Fig. 3—, which brushes are mounted on the short 20 vertical shaft —30— journaled in the bracket —31— attached to the inner guard —26—. This shaft is rotated through the medium of the pulley —32— on said shaft; pulley —33— on the vertical shaft —16— 25 and the belt —34—. As the shells reach these brushes, the lower brush will throw back the outer shell of the two riding abreast, while the upper brush will remove the upper one of two shells that may be riding on 30 top on another so that, only one shell at a time is permitted to enter the mouth of the channel way —d— at the point —b—. As the shells are carried through this channel way while resting on the outer edge of the 35 dial, they are maintained in a recumbent or horizontal position by means of the wire —35— strung through the bridges —27—, and when they leave the main channel —d— they will fall by gravity down the incline 40 channel —e—, one at a time, upon the platform —36— Figs. 1— and —4— where the shell so located is pushed off into the opening —37— as follows: 38— is a slide mounted in the block —39— and —40— is a lever 45 pivotally supported on the pin —41—. One end of this lever carries the roll —42— to engage a groove in the face cam —43— mounted on the vertical driving shaft —16—. The other end of this lever has the notch —40^a— 50 adapted to engage with the pin —44— projecting up from the slide —38—. 45— is a spring lying between lever —40— and the projection —46— of the slide. When, therefore, a shell has been deposited from the 55 channel —e— upon the platform —36—, the slide or pusher —38— will be advanced to force the shell into the opening —37—. Should, however, it occur that a shell had not dropped entirely out of the channel, and 60 to avoid its being bruised by the slide, the spring will present a flexible resistance and check the further forward movement of the slide which will remain in its halted position until the throw of the cam —43— has 65 returned said slide, when, before its next

forward movement, the shell will have been ejected from the channel by another shell falling against it and, as the platform is only wide enough to accommodate one shell at a time, there can be nothing to prevent the shell being pushed off the platform once it is fairly seated thereon.

As it is imperative that the shells be delivered head foremost to the loading machine—not shown—in the room below, they 75 will be properly turned by means of the wedge shaped bridge —47— Figs. 1— and —4—, which bridge spans the opening —37— and is located just below the platform —36— and is central with said opening. Now, when a shell drops into the opening it strikes the upper narrow edge of the bridge and, the head being the heaviest, will naturally tilt downward and drop in that 80 position into the receiving tube —48— whence it will be delivered into the conveyor bar of the loading machine—not 85 shown—in the story below.

To avoid bruising the shells by a long drop from the upper end of the delivery 90 tube —48— to the machine on the floor below, this tube is filled with shell on first starting the machine and, as the shell feeding machine is driven from the loading machine—not shown—, through the medium of 95 the shaft —16—, it is quite evident that the two machines will be so timed that the delivery tube will always remain full, therefore, when a shell is deposited onto the conveyor bar of the loading machine, another 100 shell will enter the upper end of said tube from the shell feeding machine. The side walls —49— Fig. 1— are made laterally adjustable so as to accommodate shells of 105 different lengths when said shells are resting on the platform —36—. Any tendency to overfeeding shells on the dial is counteracted by the central hole —50—, communicating with the inclined chute —51—, whereby the excess or overflow is returned to the 110 hopper —1—.

From the foregoing description it will readily be seen that shells may be delivered on the dial in any position either recumbent or erect and in any quantity until a certain point is reached when they are made to assume a recumbent position and are continuously delivered head foremost through a tube to a loading machine or machine of like character.

Having thus described my invention what I claim as new and desire to secure by Letters Patent is:

1. In a cartridge shell feeding machine, a rotatable dial having an incline face and a beveled edge of greater pitch or inclination than such face, an inner and an outer stationary guard spaced to form a channel-way through which the shells are carried by the dial and delivered outside thereof,

said inner guard made shorter than the outer guard so as to form a mouth for the channel-way, means to prevent the entrance of more than one shell at a time therein,
5 and means to prevent the shells assuming an upright position while in said channel-way.

2. In a cartridge shell feeding machine, a shell receiving tube having a narrow bridge 10 spanning the same and central therewith and located below the mouth of the tube, combined with shell feeding mechanism

adapted to feed the shells in a path at right angles to the axis of the tube so that when the shell contacts or falls on said bridge, it 15 will be tilted by gravity and fall head foremost into the tube.

Signed at Bridgeport in the county of Fairfield and State of Connecticut this 5th day of Aug. A. D. 1907.

HOWARD D. HODGE.
